[57] CLAIM

The ornamental design for an extensible support, as shown
and described.

DESCRIPTION

FIG. 1 is a perspective view of the extensible support,
showing my new design;

FIG. 2 is a left side elevation of the extensible support;

FIG. 3 is a rear elevation thereof;

FIG. 4 is a top elevation thereof; and,

FIG. 5 is a bottom elevation of the extensible support
illustrated in FIGS. 1-4.
